UNITED STATES PATENT OFFICE.

HANS OTTO SWOBODA, OF EDGEWOOD BOROUGH, PENNSYLVANIA, ASSIGNOR TO THE
MOFFAT STOVE COMPANY OF WESTON, LIMITED, OF WESTON, ONTARIO, CANADA.

ELECTRIC HEATING ELEMENT.

1,170,943.

Specification of Letters Patent.

Patented Feb. 8, 1916.

Application filed August 16, 1915. Serial No. 45,776.

To all whom it may concern:

Be it known that I, HANS OTTO SWOBODA, of the borough of Edgewood, county of Allegheny, State of Pennsylvania, United States of America, a citizen of the United States of America, have invented certain new and useful Improvements in Electric Heating Elements, of which the following is a specification.

10 This invention relates to heating elements of the type in which resistance coils are supported on a base of insulating material, and my object is to devise an easily assembled element which is easily inspected, cleaned and repaired.

I attain my object by means of a construction which may be briefly described as follows. An open-center frame is provided of insulating material, having in its face at two opposite sides sets of grooves, each end of each groove being open to the central opening of the frame. Similar sets of grooves are preferably formed in the other faces of said sides and two independent resistances 25 are strung from side to side of the frame and through said grooves. Suitable holes and grooves are provided whereby the connections between said resistances and three terminals may be made at the same face of the frame. A removable deflector is provided, adapted to fit within the frame and having grooves formed in one face to receive the portions of the resistances crossing the central opening of the frame.

30 The element is constructed in detail substantially as hereinafter described and illustrated in the accompanying drawings in which—

Figure 1 is a plan view of a heating element constructed in accordance with my invention; Fig. 2 a sectional view on the line *a—a* in Fig. 1; Fig. 3 a fragmentary section on the line *b—b* in Fig. 1; Fig. 4 a sectional view on the line *c—c* in Fig. 1; and Fig. 5 a sectional view on the line *d—d* in Fig. 1.

In the drawings like numerals of reference indicate corresponding parts in the different figures.

50 1 is an open centered frame of porcelain or other suitable insulating material provided with the binding posts or terminals 2, 3 and 4. Each binding post is preferably of the form shown in Fig. 3, which is pro-

vided with the head 5 lying in the recess 6 in the frame and is secured to the frame by the nut 7. The projecting end 8 of each binding post is preferably split to provide yielding fingers which are adapted to be received in sockets 9 carried by the insulating blocks 10 fastened to the supports 11 and 12 in any well known manner. In connection with this frame I preferably employ two independent resistances, the circuit of one resistance being from the binding post 2 to the binding post 3, and the circuit for the other from the binding post 2 to the binding post 4.

In one face of the frame at opposite sides are formed the grooves 20 and 21, which 70 grooves are preferably semi-circular and have their ends open to the central space within the frame. Similar grooves 16 and 17 are formed in the other face of these same sides of the frame, the grooves on opposite 75 sides breaking joint with one another as shown. Grooves 13, 22 and 23 are formed in one face of the frame, the grooves 13 and 22 extending to the binding post 2 and the groove 23 to the binding post 4. The other 80 end of each groove opens through one of the sides of the frame as shown.

14 is an opening through the plate communicating with the groove 13 at one side and with a groove 15 at the other side, this 85 groove opening through the edge of the side of the frame into the central space. An opening 19 is formed through the other side of the frame communicating with the groove 38 in the under face of the side of the frame 90 and opening through the side of the frame into the central space. This opening 19 also communicates with the groove 39 leading toward the binding post 3.

The various grooves opening through the 95 sides of the frame are so located that the heating resistances employed may be strung across the frame from side to side to form substantially parallel sections. Two resistances are employed forming a plurality of 100 sections alternating with one another. The resistance B, whose leads are connected respectively with the binding posts 2 and 4, is led through the grooves in one side of the plate. The resistance A, whose leads are 105 connected respectively with the binding posts 2 and 3, is led through the grooves 13 and opening 14 and through the grooves on

the other side of the plate, finally being brought through the opening 19 and led to the binding post 3.

The exposed sections of the resistance are preferably formed of coils as shown, the connecting portions lying in the grooves in the frame being preferably formed of uncoiled portions of the wire. In connection with this frame I provide a removable heat deflector 33 formed of electric and heat insulating material such as porcelain. This deflector is preferably provided with a plurality of ribs 36 forming grooves in which the coiled sections of the resistance lie. 5 This heat deflector is preferably supported as follows. Carried by the supports 11 and 12 is the frame 25, from which depend pins 26, 27 and 28 which lie in notches 29, 30 and 31 in the frame 1, and each of which is 10 provided with a spring pressed turn button 32 adapted to swing under the frame 1 and beneath the deflector 33, (see particularly Figs. 2, 4 and 5.) The corners 34 of the deflector, it will be seen, abut against fillets 15 35 formed in the frame, so that the deflector is properly positioned in respect to the latter. When it is desired to remove the deflector from the frame it is merely necessary to swing the turn buttons 32 out of the 20 locking positions, when the frame 1 may be removed and access to the resistance may be readily had for the purpose of inspection or repair. If desired, a cover or lid 37 may be 25 employed, and this cover may be either perforated or unperforated.

What I claim as my invention is:—

1. An electric heating element comprising an open-center frame of insulating material; a continuous electric resistance strung 40 back and forth across said frame to form a plurality of resistance sections, grooves being formed in one face of said frame to receive the portions of said resistance connecting said sections; and a second continuous 45 electric resistance strung back and forth across said frame to form a plurality of resistance sections alternating with and in the same plane as the sections of the other resistance, grooves being formed in the 50 other face of said frame to receive the connecting portions of said second resistance.

2. An electric heating element comprising an open-center frame of insulating material; a continuous electric resistance strung 55 back and forth across said frame to form a plurality of resistance sections, grooves being formed in one face of said frame to receive the portions of said resistance connecting said sections; a second continuous electric resistance strung back and forth across 60 said frame to form a plurality of resistance

sections alternating with and in the same plane as the sections of the other resistance, grooves being formed in the other face of 65 said frame to receive the connecting portions of said second resistance; a plurality of terminals connected to said frame; and leads from the terminals to the resistances, grooves being formed in one face of said frame to receive 70 said leads and holes in the frame through which leads may pass to the resistance having its connecting portions lying in grooves at the other side of the plate.

3. An electric heating element comprising 75 an open-center frame of insulating material; a continuous electric resistance strung back and forth across said frame to form a plurality of resistance sections, grooves being formed in one face of said frame to receive the portions of said resistance connecting 80 said sections; a second continuous electric resistance strung back and forth across said frame to form a plurality of resistance sections alternating with the sections of the other resistance, grooves being formed in 85 the other face of said frame to receive the connecting portions of said second resistance; and a removable deflector of heat insulating material fitted into the open center 90 of the frame beneath the resistance.

4. An electric heating element comprising 95 an open-center frame of insulating material; a continuous electric resistance strung back and forth across said frame to form a plurality of resistance sections, grooves being formed in one face of said frame to receive the portions of said resistance connecting 100 said sections; a second continuous electric resistance strung back and forth across said frame to form a plurality of resistance sections, 105 alternating with the sections of the other resistance, grooves being formed in the other face of said frame to receive the connecting portions of said second resistance; a plurality of terminals connected to said frame; and leads from the terminals to the resistances, grooves being formed in one face of said frame to receive 110 said leads and holes in the frame through which leads may pass to the resistance having its connecting portions lying in grooves at the other side of the plate; and a removable deflector of heat insulating material fitted into the open center of the frame beneath 115 the resistance.

Signed at Pittsburgh, Pa., U. S. A., this 16 day of June, 1915, in the presence of the two undersigned witnesses.

HANS OTTO SWOBODA.
